[57] CLAIM

The ornamental design for core sample extracting tool, as shown and described.

DESCRIPTION

FIG. 1 is a perspective view of a core sample extracting tool showing my new design;

FIG. 2 is an environmental front elevational view thereof, the rear being a mirror image;

FIG. 3 is a side elevational view thereof, the opposite side being a mirror image;

FIG. 4 is a bottom plan view thereof; and,

FIG. 5 is a top plan view thereof.

The phantom lines showing the lower torso of a human figure and a core sample form no part of the claimed design.

FIG. 1

FIG. 2

FIG. 3

FIG. 4

FIG. 5
